UNITED STATES PATENT OFFICE.

ERNEST H. PEABODY AND DAVID J. IRISH, OF NEW YORK, N. Y., ASSIGNEES TO THE BABCOCK & WILCOX COMPANY, OF BAYONNE, NEW JERSEY, A CORPORATION OF NEW JERSEY.

ATOMIZER OR SPRAYING DEVICE.

1,102,352.

Specification of Letters Patent.

Patented July 7, 1914.

Application filed September 22, 1911. Serial No. 650,857.

To all whom it may concern:

Be it known that we, ERNEST H. PEABODY and DAVID J. IRISH, citizens of the United States, residing, respectively, in New York city, borough of Manhattan, county of New York, and State of New York, and New York city, borough of Richmond, county of Richmond, and State of New York, have invented certain new and useful Improvements 10 in Atomizers or Spraying Devices, of which the following is a specification.

Our invention relates to an atomizer or spraying device by which we are enabled to vary the amount of liquid sprayed in a 15 given time without changing the initial pressure or temperature of the liquid. In other words, the present device contains within itself, a means for varying the capacity of the atomizer. It frequently happens that such 20 variation of capacity is desirable in practice, particularly when a small number of burners are in use.

While we refer to the device hereinafter described as an atomizer for liquids, we 25 purpose using it more particularly as an atomizer for liquid fuel, or so-called oil burner.

The invention will be understood by reference to the accompanying drawings in 30 which—

Figure 1 is a longitudinal section; certain parts being in elevation, of one form of atomizer embodying our invention. Fig. 2, an end view of the tip. Fig. 3, a longitudinal section on the plane of the line 3, 3, of Fig. 2. Fig. 4, a transverse section on the plane of the line 4, 4, of Fig. 5. Fig. 5, a longitudinal section on the plane of the line 5, 5, of Fig. 4. Fig. 6, a side view partly in 40 section of another form of atomizer embodying our invention. Fig. 7, an end view of the tip of Fig. 6. Figs. 8, 9, 10, details of part of the atomizer of Fig. 6. Fig. 11, a longitudinal section of another form of 45 atomizer embodying our invention. Fig. 12, an end view of the spindle handle of Fig. 11. Fig. 13 an enlarged detail view of the tip end of Fig. 11, and Fig. 14, a broken section on the plane of the line 14, 14, of 50 Fig. 11.

Similar reference numerals indicate similar parts in the several views.

In its broadest aspect, our invention consists of a device wherein the oil or other 55 liquid to be atomized is delivered from the

supply pipe to the tip chamber through one or more holes, and a spindle or plunger movable in said chamber to control the inlet area to said chamber; that is, to control the area of the single opening thereto or the 60 number of inlets, if there are more than one.

In Figs. 1 to 5, we have shown one form of the invention in which pipe 1 leads from the source of liquid supply and is provided with 65 a valve 2. By means of a suitable coupling 3, we connect a pipe 4 to the supply pipe 1 and in the forward end of pipe 4 locate the atomizing tip. This tip as shown, comprises a plug 5 preferably screwed into the 70 end of pipe 4, and a cap 6 seated on the end of said plug and having an outlet orifice 7. The plug 5 has a central longitudinal bore, and one or more longitudinal passages 8, two such passages being shown, which are 75 closed at their outer ends by cap 6. In the wall between the passages 8 and the central bore of the plug 5, ducts 9 are provided tangential to the wall of said bore, said ducts affording a communication for the flow of 80 liquid from pipe 4 to the tip outlet. To control the working area of said ducts—that is, to open them more or less or to completely close them, we provide a spindle 10, the forward end of which is of such diameter as to snugly fit into the central bore of plug 5. To effect the necessary longitudinal movement of said spindle, it is formed with a screwthread 11, which passes through an interiorly threaded collar or nut 12 closing the end of nipple 3. To manipulate the spindle 10, a suitable hand wheel 13 is provided.

When the atomizer is not in use, the hand wheel 13 will have been turned to advance 95 spindle 10 within the central bore of plug 5 so as to completely cover the outlets of ducts 9. If the tangential ducts 9 extend to the end of plug 5, then the spindle will be seated against cap 6. When the atomizer is to be put in use, the wheel 13 is turned to withdraw the spindle 10 to uncover the outlets of the tangential ducts a distance sufficient to permit the flow of the desired 100 amount of liquid. When spindle 10 is withdrawn the desired distance, a chamber 14 is formed in the central bore of plug 5 between the end of said spindle and cap 6 into which the liquid flows, and by reason of the arrangement of ducts 9, the liquid will be 110

given a rapid whirling motion in said chamber by which it is atomized when it passes the outlet orifice 7.

Should it be desired to vary the amount 5 of liquid sprayed in a given time, it may be done without changing the pressure or the temperature of the liquid by simply adjusting spindle 10 to vary the area of the opening of the ducts 9. The latter being in the 10 same transverse plane the movement of spindle 10 opens or closes each duct an equal amount. The pitch of screw 11 may be such as to completely or only partially open the ducts 9 for one complete revolution of 15 hand wheel 13.

In Figs. 6 to 10, we have shown a form 20 of the invention in which the tip is provided with a series of holes in different transverse planes. In this form, the supply pipe 1 delivers the liquid through a suitable coupling to a pipe 15. Instead of making the tip in two parts as in Figs. 1 to 5, we make it in a single piece having a flange 16 by which it may be clamped to 25 the end of pipe 15 by a cap 17; the discharge orifice 18 being centrally located in the tip and the outer end of the tip fitting snugly the wall of a central opening in the cap, as shown in Fig. 6. The inwardly extending neck 19 of the tip is of less diameter than the interior diameter of pipe 15 and is formed with a series of ducts 20 tangential to the central bore 21 thereof. The bore 21 is contracted at the outer end 30 of the tip to form the outlet orifice and thus provide a seat for spindle 22 when it is moved to close all of the ducts 20. The spindle 22 is threaded similarly to the spindle 10 of Fig. 1 and is advanced or retracted 35 by turning the hand wheel 23. The ducts 20 are arranged in a spiral path around the neck 19 so that they are in different transverse planes and the distance longitudinally between them may be such that for a given 40 extent of movement of the hand wheel 23, the spindle 22 will be retracted to start the uncovering of one of the tangential ducts 20 just as the one preceding it has been completely opened. However arranged as to 45 the longitudinal distance between them, the result is that when the spindle is retracted, a greater amount of liquid will be permitted 50 to enter the chamber 21 through the tangential ducts while maintaining the initial pressure in the pipe 1 substantially constant; and, conversely, the amount of liquid may be reduced by advancing the spindle to close some of the tangential ducts without a decrease of the initial pressure in the pipe 1.

In Figs. 11 to 14 inclusive, we have shown 60 still another form of our invention embodying the same principle of operation and containing some additional features which assist in the manipulation of the device. In this form, the supply pipe 1 is fitted to

an elbow 24 to which the pipe 25 is also connected. Resting on the outer end of pipe 25 and clamped thereto by means of a cap 26, is a tip 27 of substantially the same form as shown in Fig. 6, except that 70 in the present form the tangential ducts 28 which permit the flow of liquid from pipe 25 to the chamber 29 formed between the end of plunger 30 and the end of the tip, are arranged as shown; that is, two or more 75 ducts are in the same transverse plane but so arranged that a given series of these ducts are on a spiral path—that is, the ducts in this tip combine the arrangement of Figs. 1 and 6. 80

The spindle at one end fits into the central bore of the tip 27 and passing through a suitable stuffing box is threaded at its outer end 31. Instead of being advanced or retracted by a rotary movement, we provide in this case for the rectilinear movement only of the plunger. To effect this, the threaded end of the plunger is engaged by a hand wheel 32 splined thereon, said hand wheel having a follower 33 which engages the screw threads; it being obvious that as the hand wheel is rotated the follower 33 will effect a rectilinear movement of the spindle without rotating the same. 90

As shown in the drawings the spindles of the several devices illustrated have an abrupt end and control only the inlet areas of the openings into the oil chamber of the tip; that is, the spindle in each construction does not have at its end a needle valve which 95 would enter and control the area of the discharge orifice. According to the present invention the total area of the discharge orifice is available at all times for the outflow of the oil when the spindle is moved to uncover the openings into the tip chamber. 100

To indicate to the attendant the extent of movement of spindle 30 or the number of ducts open through tip 27 when the spindle is retracted, we provide a scale on the face 110 of hand wheel 32 the divisions of which correspond to the pitch of screw 31, or a given movement of the spindle which will open a greater or less number of the ducts in the tip for a partial revolution of the hand wheel. This is a mere matter of convenience and may be arranged as desired. We have shown the hand wheel so divided that the movement from zero to 1 may completely open the first row of ducts, and the movement from 1 to 2 may open the second row, etc. This, however, may be arranged as desired. The bracket 34 which forms a continuation of the elbow 24 may be turned upwardly in front of the hand wheel to form a 115 pointer 35. To hold the hand wheel to any adjusted position, we provide notches 36 on the rear thereof, which notches are adapted to be engaged by a spring-pressed-finger 37.

On the face of hand wheel 36, is a groove 120

38 into which projects a stud or pin 39 supported on bracket 34. The groove 38 is not continuous around the face of the hand wheel, as indicated in Fig. 12, thus providing two shoulders 40 to thereby limit the rotation of the hand wheel when engaged by the stop pin 39. That is, when the hand wheel is turned to zero position, the plunger will be advanced so that its end will rest 10 against the seat formed by the tip so as to close all of the ducts in the tip. The stop pin 39 will then engage one of the shoulders. When the hand wheel is turned to its other extreme position, the spindle 30 will have 15 been moved sufficiently to open all of the ducts 28 and the stop-pin 39 will engage the other shoulder.

What we claim and desire to secure by Letters Patent of the United States is:—

- 20 1. In an atomizer or spraying device, a supply pipe, a tip having a discharge orifice and an oil chamber, the wall of said chamber having lateral or side openings communicating with the supply pipe, and an abrupt ended member movable in said chamber and operable from without the supply pipe to control only the inlet area of said openings and to leave the discharge orifice free for the flow of the oil.
- 30 2. In an atomizer or spraying device, a supply pipe, a tip having a discharge orifice and an oil chamber, the wall of said chamber having lateral or side openings communicating with the supply pipe and 35 tangential to said chamber, and an abrupt ended member movable in said chamber and operable from without the supply pipe to control only the inlet area of said openings and to leave the discharge orifice free for 40 the flow of the oil.

3. In an atomizer or spraying device, a supply pipe, a tip having a discharge orifice and an extension with a central chamber, said extension having lateral or side openings therein communicating with the supply pipe and tangential to the said chamber, and an abrupt ended member movable in said chamber and operable from without the supply pipe to control only the inlet area of said openings and to leave the discharge orifice free for the flow of the oil. 45

4. In an atomizer or spraying device, a supply pipe, a tip having a neck with a longitudinal bore, said neck being of less diameter than the internal diameter of the supply pipe and having ducts in the wall thereof to permit the flow of liquid to the bore of the neck, and an abrupt ended member movable in said chamber to control only the inlet area of said ducts and to leave the discharge orifice free for the flow of the oil. 50

5. In an atomizer or spraying device, a supply pipe, a tip having a neck with a longitudinal bore, said neck being of less diameter than the internal diameter of the supply pipe and having ducts in the wall thereof tangential to said bore, a spindle seated in said bore, said spindle having an abrupt end so as to leave the discharge orifice free for the flow of the oil, and means for moving 65 said spindle to control the inlet area of said ducts.

In testimony whereof we have hereunto signed our names in the presence of two subscribing witnesses.

ERNEST H. PEABODY.

DAVID J. IRISH.
